Attorney

UNITED STATES PATENT OFFICE.

FRANK T. DICKSON, OF BALTIMORE, MARYLAND.

TOY.

1,321,899.

Specification of Letters Patent. Patented Nov. 18, 1919.

Application filed June 28, 1919. Serial No. 307,390.

To all whom it may concern:

Be it known that I, FRANK T. DICKSON, a citizen of the United States, residing at Baltimore, in the State of Maryland, have 5 invented certain new and useful Improvements in Toys, of which the following is a specification.

This invention relates to toys, and more particularly to wheeled toys.

10 The object of the invention is to provide a wheel toy with a figure which is rocked back and forth from the hips as the toy is run along the ground.

Another object is to provide a toy of this 15 character which is extremely simple in construction, and made in the shape of a row boat with an oarsman therein, connected to operating means actuated by the supporting wheels, whereby in the backward and 20 forward movements of the device, a rowing motion will be imparted to the figure.

Another object is to so construct such a 25 toy that the figure constituting a part thereof may be easily connected and disconnected from its operating mechanism.

With the foregoing and other objects in view, which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention.

In the accompanying drawings:—

Figure 1 represents a longitudinal central section of a toy constructed in accordance 40 with this invention,

Fig. 2 is a top plan view, thereof, and

Fig. 3 is a transverse section taken on the line 3—3 of Fig. 2.

The toy constituting this invention comprises a body 1 in the form of a row boat, 45 mounted on rear supporting wheels 2 and a smaller front wheel 3, the latter being mounted midway the width of the pointed end of the boat body with its upper portion housed therein as shown clearly in Fig. 1, 50 said pointed end or bow of the boat being shown solid.

A seat shown in the form of a cross bar 4 extends transversely of the body member 55 1 and has a recess 5 in its rear edge provided with a centrally disposed extension 6, the

rear wall of which is beveled as shown at 7 to permit the body 8 of the figure forming a part of the invention to rock backward into said recess.

60

The figure 8 which may be of the grotesque form illustrated, or of any other form, has the lower end of its body pivotally mounted on a pintle 9 mounted in the end walls of the recess 5 so that when said body 8 is 65 rocked, it will move backward into the recess extension 6 as shown in Fig. 1.

Legs 10 are positioned on opposite side faces of the body 8 and pivoted at their ends on the pintle 9 and are provided at 70 their lower ends with feet 10^a which normally rest loosely on the bottom of the boat body, as shown clearly in Figs. 1 and 3. These legs 10 as illustrated, are positioned at the ends of the recess 5, whereby the body 75 8 is centralized to adapt it to move backward into the recess extension 6 when rocked.

Arms 11 are pivotally mounted at one end on pins 12 which project laterally from the shoulders of the body 8, and the free ends 80 of these arms, which are preferably shaped to represent clenched hands, are loosely engaged with crank axles 13 and 14 which support the wheels 2, the free inner ends of said axles being spaced a sufficient distance 85 apart to permit them to clear each other when rotated, and when it is desired to disengage the arms of the figure therefrom, one of said axles is turned out of alignment with the other, and the arms slipped off said axle, 90 sufficient play being provided at the shoulders to permit this.

When the figure 8 is connected with the axles 13 and 14 as shown in the accompanying drawing, and the toy is moved forward 95 or backward over a supporting surface, the crank axles 13 and 14 will, through the arms 11 impart a rocking motion to the body 8 of the figure from the hip line, where it is pivoted on the pintle 9. This rocking motion simulates the motion of an oarsman and will be found very amusing to children.

From the foregoing description, taken in connection with the accompanying drawings, the advantages of the construction and of 105 the method of operation will be readily apparent to those skilled in the art to which the invention appertains and while I have described the principle of operation of the invention together with the device which I 110 now consider to be the best embodiment thereof, I desire to have it understood that

the device shown is merely illustrative and that such changes may be made as are within the scope of the claimed invention.

Having thus fully described my invention, 5 what I claim as new and desire to secure by Letters Patent, is:—

A toy of the class described comprising a vehicle body having a bar extending transversely thereof and provided with a recess 10 in its rear edge, a centrally disposed extension in said recess, the rear wall of said extension being beveled, a pintle mounted in

said recess, a figure having the lower end of its body pivotally mounted on said pintle to permit the figure when rocked to move backward into the extension of said recess, legs pivoted at one end on said pintle on opposite sides of the body of said figure and at the ends of said recess to centralize the body of the figure and adapt it to move backward 20 into the recess extension, and means for actuating said figure.

In testimony wherof I affix my signature.

FRANK T. DICKSON.
